UNITED STATES PATENT OFFICE.

NOYES F. PALMER, OF BROOKLYN, NEW YORK.

DESIGN FOR A FOUNTAIN-PEN NOZZLE.

SPECIFICATION forming part of Design No. 19,349, dated October 8, 1889.

Application filed September 2, 1889. Serial No. 322,793. Term of patent 14 years.

To all whom it may concern:

Be it known that I, NOYES F. PALMER, of Brooklyn, New York, have invented and produced a new and original Design for a Fountain-Pen Nozzle, of which the following is a specification, reference being had to the accompanying drawings, forming part thereof.

Figure 1 is a side view of my newly-designed fountain-pen nozzle. Fig. 2 is a section on line $x x$, Fig. 1.

The leading feature of my design consists of a tube having a threaded extension and of a knurl surrounding the tube in front of the threaded extension, the knurl having a concave surface.

A is a tube having at its rear end a threaded

extension a . Forward of this extension the tube A is surrounded by an annular knurl or projection b . This knurl has a concave surface, being lowest at the center and rising toward the ends.

What I claim is—

The design for a fountain-pen nozzle, consisting of tube A, having a threaded extension a , and of a knurl surrounding the tube in front of the threaded extension, the knurl having a concave surface, substantially as shown.

NOYES F. PALMER.
